UNITED STATES PATENT OFFICE

2,480,012

BELT LOOP SEWING MACHINE

Joseph Galkin, New York, N. Y.

Application February 13, 1948, Serial No. 8,100

8 Claims. (Cl. 112—2)

1

This invention relates to improvements in cup feed sewing machines whereby belt loops are automatically produced in a single continuous operation by mechanism comprising two blades movable lengthwise of the line of feed which cut an untrimmed section of fabric into strip form, then forms a ridge in the middle of the strip and upfolds both edges of the strip, the mechanism being adapted to automatically and simultaneously top feed the untrimmed section of fabric and the trimmed strip of fabric with a four-motion feeding mechanism while the strip is flat and then continues to feed the strip of fabric when ridged and upfolded and then feeds the folded loop while being overedge stitched.

In my prior Patent No. 2,262,547, I have disclosed mechanism for producing belt loops having edge portions in abutting relation and stitched by two spaced needles which caused two threads to pass through and be visible on the upper and lower surfaces of the belt loops.

An object of this invention is to provide mechanism for producing belt loops from an untrimmed section of fabric or from scrap material, and in which the stitching is not visible on the normally exposed surface of the fabric and which is produced automatically in a single continuous operation by top-feeding, trimming lengthwise of the line of feed, upfolding, and overedge stitching operation.

Another object of this invention is to provide a work supporting base of a size adapted to support a large section of untrimmed fabric and having an upper surface level with a stationary blade to facilitate handling of large sections of fabric to be cut into pre-determined width, the base having a chute through which the chips move downwardly from the base, whereby continued belt loop making operation is possible with overedge stitching at high speed.

Another object of this invention is to provide a fabric guide to accurately space one edge of the section of fabric in relation to the cutting blades to trim a minimum of fabric at one edge thereof.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

2

Figure 1 is a top plan view of a cup feed overseaming machine, showing my invention applied thereto.

Figure 2 is a front elevation of the sewing machine shown in Figure 1.

Figure 3 is an end view of the machine shown in Figures 1 and 2.

Figure 4 is a top plan view of a fragmentary portion of the four-motion top feed-dog and the duplex trimming mechanism, the feed dog actuating mechanism being removed.

Figure 5 is a front view of the mechanism shown in Figure 4, above the work supporting base.

15 Figure 6 is a top plan view similar to that shown in Figure 4, with the top feed-dog removed to show the stationary blade.

Figure 7 is a cross-sectional view taken on the line 7—7 in Figure 6.

20 Figure 8 is a cross-sectional view taken on line 8—8 in Figure 4, a portion of the housing for the feed-dog being shown and the feed-dog actuating mechanism being omitted.

Figure 9 is a view showing the formation of 25 a blind stitched belt loop, on an enlarged scale.

Figure 10 is a cross-sectional view taken on line 10—10 in Figure 1.

In the illustrated embodiment of the invention, the numeral 10 indicates the work supporting base of a sewing machine embodying my invention and which comprises a casing 11, two cup-shaped feeding disks 12, 12, a horizontal needle 13, a looper 14, and a deflector 15 for both needle and looper thread loops. A stitch finger 30 is shown at 16. A plate having the needle guiding groove is shown at 17, a needle thread guide is shown at 18 and a looper thread guide at 19, as is known in the art.

This invention is particularly directed to a 40 duplex automatic feeding and trimming mechanism 25. The automatic feeding mechanism comprises a combined four-motion top feed-dog 26 having a forward rectangular strip feeding portion 27, an intermediate triangular convergingly feeding portion 28 and a bifurcated rear portion 29. The top feed-dog 26 has feeding teeth 30 extending all along the length thereof on its lower surface. The feeding mechanism is designed to feed a large section of fabric or scrap material to and through a duplex trimming mechanism, through a convergingly folding section 31, past a central fin 32 between the bifurcated rear feeding portion 29 and to the cup-shaped feeding disks 12.

55 The duplex automatic trimming mechanism

35 comprises a stationary blade 36 having a horizontal rectangular upper surface 37 and two cutting edges 38, in the desired spaced-apart strip cutting relation.

The movable shear blades 40, 40' are supported by blade carriers 41. The movable blade carriers are slidably mounted on a rock-shaft 42. The carriers 41, 41' are keyed to the shaft 42 by a key 43 and are resiliently pressed by coil springs 44 in the direction of the stationary cutting edges 38.

The movable shear blades 40, 40' thus cooperate with the cutting edges 38 of the stationary shear blade 36 to cut a fabric strip of predetermined width.

The movable shear blades 40, 40' are given substantially vertical movements by the carriers 41, 41'. The carriers slidably engage the elongated key 43. The key is held in fixed parallel relation with the rock-shaft 42 by being held in an arm 45 fixed to the shaft 42.

An arm 46 is fixed to one end of the shaft 42 and is pivotally connected to a ball-jointed vibrating connecting rod 47 operated by an arm 48 on a rock-shaft 49. The rock-shaft 49 actuates the movable shear blades 40, 40' once for each revolution of the main shaft 50. The rock-shaft 49 has an arm 51 fixed thereto. The free end of the arm 51 is pivotally connected to a ball-jointed vibrating connecting rod 52, the upper end of which is suitably actuated by an eccentric 53 on the main shaft 50. The shaft 49 is thus rocked by the eccentric 53 on the main shaft 50.

As shown in Figure 4, there are provided two folding members 55 which are secured to the work supporting base 10 by screws 56. The folding members 55 comprise converging upright walls 57 which are in closely spaced relation from the converging side walls of the intermediate triangular portion 28 of the feed-dog 26. When the trimmed strip fabric passes the converging portion 28 of the feed-dog 26, the converging upright walls 57 cause the side edge portions of the fabric to fold upwardly due to the constantly constricting passageway between the said walls.

Suitably secured to the walls 57 by leaf springs 58 are sideways movable folder members 59 having upright inner walls which are positioned parallel with the outer faces of the bifurcated rear portion 29 of the feed-dog 26.

The forward end of the rectangular strip feeding portion 27 of the top feed-dog 26 extends forwardly of the movable shear blades 40, 40' and feeds the fabric to and through the movable shear blades.

The intermediate triangular converging portion 28 in coacting relation with the upright folder walls 57 fold the trimmed strip into U-shaped form.

The resiliently held and sideways movable folder members 59 coact with the bifurcated rear portion of the feed dog to retain the U-shape of the fabric while the central fin or tongue 32 crimps the crosswise bottom portion of the U-shaped fabric upwardly to cause the needle 13 and looper threads to cover the side edges of the folded fabric and to blindstitch the middle of the crimped loop to the U-shaped fabric.

Figure 9 is an enlarged scale diagram showing the formation of a blind stitched belt loop, the bite of the needle 13 into the fabric being regulated by pivoting the rear portion of the central fin 32. The fin 32 is finely adjustable vertically to and from the needle 13 to enable the bite of the needle to be varied. The needle passes

through the edges of both side portions of the fabric and through the central portion down-folded over the fin 32.

The top feed-dog 26 has an upright central wall 60. The front portion of the feed-dog has a guide slot 61 with parallel upright walls.

As shown in Figure 3, a crank 62 is secured to a rock-shaft 63. The free lower end of the crank 62 is operatively positioned in the guide slot 61. The shaft 63 is rotatably mounted in a bearing 64 which is fixed to the work supporting base 10 by screws 65.

Suitably secured to the shaft 63 is an arm 66 at the free upper end of which is connected a link 67. The link 67 is connected to a crank 68 fixed to the rock shaft 42.

It will thus be seen that the feed-dog 26 is moved forward and backward by the rock shaft 42 and through the arms 46 and 48 and the rock shaft 49 and the connecting rod 52, the feed-dog 26 derives its forward and backward motions from the eccentric 53 on the main shaft 50.

The up-and-down movements of the feed-dog 26 are imparted from a lever 70 fixed to a bushing 71 in the bearing 64. The lever 70 (Figure 1) is horizontally positioned below and in supporting relation with a pin 72 extending transversely of the feed-dog.

Fixed to the bushing 71 (Figures 1 and 10) is a lever 73 having its free end 74 below the free end portion of a lever 75 which is fulcrumed on a pin 76. The lever 75 is connected at one end to a connecting rod 77 which is actuated by an eccentric 53a on the main shaft 50.

It will thus be seen that the feed-dog 26 receives its four motions forward, backward, and up and down from the main shaft 50.

As shown in Figures 8 and 9, the central fin 32 is pivoted at the front end on a pin 78. At the rear end, the fin 32 has an integral lower extension 79 which terminates in a threaded rod 80 passing through a horizontal arm 81 fixed to the lower surface of the work supporting base 10.

A coil spring 82 is interposed in compressed relation between the extension 79 and the arm 81. A threaded nut 83 mounted on the lower end of the threaded rod 80 makes it possible to compress the spring 82 and thereby lower the fin 32 as determined by the point of penetration of the needle 13 into the upfolded loop material, as shown in Figure 9.

It is to be noted that the feed-dog 26 is resiliently pressed against the work supporting base 10 by two coil springs 33 which are mounted for vertical motion in apertures 34 in a housing 54 and react against pins 69 extending upwardly from the feed-dog. A leaf spring 84 is suitably secured to the feed-dog and reacts against the housing 54 and assists in stabilizing the horizontal position of the feed-dog.

A fabric guide 85 is secured to the work supporting base 10 by a screw 86. The guide 85 serves to accurately space one edge of the section of fabric operated on in relation to the cutting blades to trim a minimum of fabric at one edge of the fabric.

I have provided an adjustable support 88 for the stationary blade 36. The support 88 comprises a block 89 to which the blade 36 is fastened.

By adjusting a screw 90 in the support 88, it is possible to raise or lower the blade 36 to bring its upper surface level with the work supporting base 10 after the blade is ground.

The overseaming sewing machine herewith

shown is of the type shown in Patent Number 1,236,599 dated August 14, 1917, and needs no further description.

In accordance with the patent statutes I have described and illustrated the preferred embodiment of my invention, but it will be understood that various changes and modifications can be made therein without departing from the spirit of the invention as defined by the appended claims.

I claim:

1. In a cup feed overseaming machine, duplex automatic feeding and trimming mechanism for producing belt loops of the class described in a continuous automatic operation, comprising a work supporting base of a size adapted to support a section of untrimmed fabric, a stationary blade having a horizontal rectangular upper surface and two cutting edges in spaced-apart strip cutting relation, said stationary blade being fixed to said work supporting base with its upper surface level with the upper surface of said base, two vertically reciprocable blades movable lengthwise of the line of feed and coacting simultaneously with said stationary blade to sever said section of fabric along parallel edges, a combined four-motion top feed-dog having a rectangular full-width strip feeding portion and a triangular convergingly feeding and folding portion for automatically feeding a horizontal flat untrimmed fabric section into vertically folded loop form, and two folding members having converging upright walls fixed to said base on opposite sides of said converging feeding portion of said top feed-dog and coacting with said converging walls in folding said strip into loop form and feeding said loop to W-shaped loop forming mechanism and to a pair of feeding cups.

2. In an overseaming machine having two feeding cups, duplex automatic feeding and trimming mechanism for producing belt loops of the class described in a continuous automatic operation, comprising a work supporting base adapted to support a section of untrimmed fabric, a stationary blade having a horizontal upper surface and two cutting edges in spaced-apart strip cutting relation, said stationary blade being fixed to said work supporting base with its upper surface at the upper surface of said base, two vertically reciprocable blades movable lengthwise of the line of feed and coacting with said stationary blade to simultaneously shear a section of fabric along parallel edges, a combined four-motion top feed-dog having a rectangular full-width strip feeding portion and a triangular convergingly feeding and folding portion for automatically feeding a horizontal flat untrimmed fabric section into vertically folded form, and two folding members having converging upright walls fixed to said base on opposite sides of said converging feeding portion of said top feed-dog and coacting with said converging feed-dog walls in folding said strip into loop form and automatically feeding said loop to said feeding cups.

3. In an overseaming machine having two feeding cups, duplex automatic feeding and trimming mechanism for producing belt loops of the class described in a continuous automatic operation, comprising a work supporting base adapted to support a section of untrimmed fabric, a stationary blade having a horizontal upper surface and two cutting edges in spaced-apart strip cutting relation, said stationary blade being fixed to said work supporting base with its upper surface at the upper surface of said base, two vertically reciprocable blades movable lengthwise of the line of feed and coacting with said stationary blade to simultaneously shear a section of fabric along parallel edges, a combined four-motion top feed-dog having a rectangular full-width strip feeding portion and a triangular convergingly feeding and folding portion for automatically feeding a horizontal flat untrimmed fabric section into vertically folded form, and two folding members having converging upright walls fixed to said base on opposite sides of said converging feeding portion of said top feed-dog and coacting with said converging feed-dog walls in folding said strip into loop form and automatically feeding said loop to said feeding cups.

reciprocable blades movable lengthwise of the line of feed and coacting with said stationary blade to simultaneously shear a section of fabric along parallel edges, a combined four-motion top feed-dog having a forward rectangular strip feeding portion and a rear triangular convergingly feeding portion for automatically feeding a horizontal flat untrimmed fabric section into vertically folded form, and two folding members having converging upright walls fixed to said base on opposite sides of said converging feeding portion of said top feed-dog and coacting with said converging feed-dog walls in folding said strip into loop form and automatically feeding said loop to said feeding cups.

4. In an overseaming machine having two feeding cups, duplex automatic feeding and trimming mechanism for producing belt loops in a continuous automatic operation and wherein the stitching is not visible on the normally exposed surface of the fabric, comprising a work supporting base adapted to support a section of untrimmed fabric, a combined four-motion top feed-dog having a forward rectangular strip feeding portion, an intermediate triangular convergingly feeding portion and a bifurcated rear portion for automatically feeding a horizontal flat untrimmed fabric section into vertically folded form, a stationary blade having a horizontal upper surface and two cutting edges in spaced-apart strip cutting relation, said stationary blade being fixed to said work supporting base with its upper surface at the upper surface of said base, two vertically reciprocable blades movable lengthwise of the line of feed and coacting with said stationary blade to simultaneously shear a section of fabric along parallel edges, and two folding members having converging upright walls fixed to said base on opposite sides of said converging feeding portion of said top feed-dog and coacting with said converging feed-dog walls in folding said strip, and four-motion mechanism for said feed-dog for automatically feeding said folded strip to said feeding cups.

5. In an overseaming machine having two feeding cups, automatic feeding and duplex trimming mechanism for producing belt loops in a continuous automatic operation, comprising a work supporting base adapted to support a section of untrimmed fabric, a combined four-motion top feed-dog having a forward rectangular strip feeding portion, an intermediate triangular convergingly feeding portion and a bifurcated rear portion for automatically feeding a horizontal flat fabric section into vertically folded form, a stationary blade having a horizontal rectangular upper surface and two cutting edges in spaced-apart strip cutting relation, said stationary blade being fixed to said work supporting base with its upper surface at the upper surface of said base, two vertically reciprocable blades movable lengthwise of the line of feed and coacting with said stationary blade to simultaneously shear a section of fabric along parallel edges, and two folding members having converging upright walls fixed to said base on opposite sides of said converging feeding portion of said top feed-dog and coacting with said converging feed-dog walls in vertically folding said strip, an upright tongue positioned intermediate said folding members, and four-motion feeding mechanism for said feed-dog for automatically feeding said fabric to said feeding cups.

6. In an overseaming machine having two feeding cups, automatic top feeding and duplex

trimming mechanism for producing belt loops in a continuous automatic operation, comprising a work supporting base adapted to support a section of untrimmed fabric, a combined four-motion top feed-dog having a forward rectangular strip feeding portion, an intermediate triangular convergingly feeding portion and a bifurcated rear portion for automatically feeding a horizontal flat fabric section into vertically folded form, a stationary blade having a horizontal rectangular upper surface and two cutting edges in spaced-apart strip cutting relation, said stationary blade being fixed to said work supporting base with its upper surface at the upper surface of said base, two vertically reciprocable blades movable lengthwise of the line of feed and coacting with said stationary blade to simultaneously shear a section of fabric along parallel edges, and two folding members having converging upright walls fixed to said base on opposite sides of said converging feeding portion of said top feed-dog and coacting with said converging feed-dog walls in vertically folding said strip, an upright tongue positioned intermediate said folding members, and four-motion feeding mechanism for said feed-dog for automatically feeding said fabric to and through said duplex trimming mechanism and to said feeding cups.

7. In an overseaming machine having two feeding cups, automatic top feeding and duplex trimming mechanism for producing belt loops in a continuous automatic operation from an untrimmed fabric section, comprising a work supporting base adapted to support a section of untrimmed fabric, a combined four-motion top feed-dog having a forward rectangular strip feeding portion, an intermediate triangular convergingly feeding portion and a bifurcated rear portion, a stationary blade having a horizontal rectangular upper surface and two cutting edges in spaced-apart strip cutting relation, said stationary blade being fixed to said work supporting base with said cutting edges positioned at the upper surface of said base, two vertically reciprocable blades movable lengthwise of the line of feed and coacting with said stationary blade to simultaneously shear a section of fabric along two parallel edges, and two folding members having converging upright walls fixed to said base on opposite sides of said converging feeding portion of said top feed-dog and coacting with said converging feed-dog walls in vertically folding said strip, an upright tongue positioned intermediate said bifurcated rear feed-dog portion and

four-motion feeding mechanism for said feed-dog for automatically feeding said fabric to and through said duplex trimming and folding mechanism and to said feeding cups.

5 8. In a blindstitch overseaming machine having a main shaft and two feeding cups having saw shaped teeth, automatic top feeding and duplex trimming mechanism for producing belt loops in a continuous automatic operation from an untrimmed fabric section, comprising a work supporting base adapted to support a section of untrimmed fabric, a combined four-motion top feed-dog having a forward rectangular strip feeding portion, an intermediate triangular convergingly feeding portion and a bifurcated rear portion, a stationary blade having a horizontal rectangular upper surface and two cutting edges in spaced-apart strip cutting relation, said stationary blade being fixed to said work supporting base with said cutting edges positioned at the upper surface of said base, two vertically reciprocable blades movable lengthwise of the line of feed and coacting with said stationary blade to simultaneously shear a section of fabric along two parallel edges, and two folding members having converging upright walls fixed to said base on opposite sides of said converging feeding portion of said top feed-dog and coacting with said converging feed-dog walls in vertically folding said strip, an upright tongue positioned intermediate said bifurcated rear feed-dog portion for crimping said folded strip and four-motion feeding mechanism for said feed-dog for automatically feeding said fabric to and through said duplex trimming and folding mechanism and to said feeding cups, said feeding mechanism being actuated from said main shaft.
